SAFETY INNER TUBE FOR PNEUMATIC TIRES

Louis Emil Walk, Drumright, Okla.

Application November 25, 1938, Serial No. 242,352

1 Claim. (Cl. 152—338)

This invention relates to new and useful improvements in safety inner tubes for pneumatic tires.

It is a well known fact that many accidents and wrecks are caused by the car striking a rock or other obstacle and being over-turned or thrown from the highway, and the primary object of my present invention is to provide a safety inner tube for pneumatic tires that will absolutely prevent accidents of this kind. This is accomplished by providing an inner tube that is divided into a plurality of individual air compartments by transverse or parallel partitions, whereby, in the event of a blow-out or puncture caused by the tire coming into contact with some obstacle in its path, only one air compartment will be affected and the remaining air compartments and air pressure will be sufficient to carry the load until a suitable or convenient place is reached for repair.

A further object of my invention is to provide a safety inner tube that will eliminate the necessity of changing tires on the highway in the event of a blow-out or puncture, thus saving time, annoyance and labor.

A still further object of my invention is to provide an inner tube construction, whereby the need of carrying the usual spare tire, inner tube and extra wheel, is eliminated.

Still another object of my invention is to provide an inner tube of the character specified that is relatively simple and economical in construction and highly efficient and durable in use.

With the foregoing and other objects in view that will appear as the nature of my invention is better understood, the same consists in the novel features of construction, combination and arrangement of parts illustrated in the accompanying drawings and more particularly pointed out in the appended claim.

In the accompanying drawings, which are for illustrative purposes only and are therefore not drawn to scale:

Figure 1 is a side elevation of a safety inner tube for pneumatic tires divided into individual air compartments by transverse partitions.

Figure 2 is a longitudinal section.

Figure 3 is an enlarged detail sectional view of the main valve stem, operating lever and associated parts.

Figure 4 is a fragmentary section of a safety inner tube divided into individual parallel air compartments which extend entirely around the tire.

Figure 5 is a transverse section, taken on line

5—5 of Figure 4 and the remaining views are details of various features of my invention.

Referring to the drawings for a more particular description of my invention, and in which drawings like parts are designated by like reference characters throughout the several views, A designates my improved safety inner tube, as a whole, which is divided into a plurality (preferably eight) of corresponding separate or individual air compartments 1, 2, 3, 4, 5, 6, 7 and 8, 10 respectively, by the transverse partitions 9. The cross partitions 9 are preferably constructed of two-ply corded rubber to prevent stretching of the partitions over three inches.

A continuous heavy rubber tube 10, about one-quarter inch in diameter, is embedded in the inner tube next to the rim and conducts air via the main valve stem 11, which is of the ordinary or conventional type, to and from the individual air compartments 1 to 8, respectively.

In carrying out my invention, the individual air compartments are provided with the quick closing valves 12, which makes it possible to inflate and deflate each compartment. Each valve 12 is suitably connected to the steel wire 13, which works in a stationary conduit 14, as shown. The conduit 14 is fixed in place by the cross members 14^a arranged in the tube 10, or other equivalent means. A valve operating shaft 15 extends through the main valve stem 11 and is formed at its inner end with an angular crank arm 16 secured, as at 17, to the steel wire 13. The conduit 14 is formed with a slot to facilitate the proper attachment and operation of the crank arm aforesaid. The outer end of the valve operating shaft 15 is preferably flattened, as at 18, and may be easily engaged and turned to shift the steel wire 13 about one-half inch to open and close the air valves 12. The body portion of the shaft 15 is held in place by the braces 19 and 20.

In practice, if a blow-out or puncture occurs in the tire casing and one of the air compartments of the inner tube, due to the car striking an obstruction of some kind on the highway, only the particular air compartment affected will be deflated and the twenty-eight pounds of air remaining in the other compartments will be sufficient to safely carry the load until a convenient place is reached to make repairs, thus saving time, annoyance and labor of changing tires on the road. Further, and most important of all, my invention provides a safety factor that will eliminate the liability of the car being over-turned or thrown from the highway when a

blow-out or puncture occurs, with the usual disastrous results.

In the form of my invention illustrated in Figures 4 and 5 of the drawings, the inner tube is divided into six corresponding individual parallel air compartments 21 by the laterally spaced circumferential partitions 22. The air compartments 21 extend entirely around the inner tube and are provided with the separate valves 23 which are operated by the master valve 24. A rubber tubing 25 carries air to and from the air compartments 21 and a steel wire 26 extends through the tubing 25 and is connected to each of the valves 23, the purpose of which will be apparent.

From the foregoing description taken in connection with the drawings, it is thought that the construction, operation and advantages of my invention will be readily understood, without requiring a more extended explanation.

Various changes in the form, proportions and

minor details of construction may be resorted to without departing from the principles or sacrificing any of the advantages of my invention as defined in the appended claim.

Having described my invention, what I claim 5 as new and desire to secure by Letters Patent, is:

A safety inner tube for pneumatic tires divided into a plurality of individual air compartments by partitions, a rubber tube embedded in the inner tube adjacent the rim, for conducting air to 10 the individual air compartments, quick closing valves for said air compartments, a steel wire connected with each of said quick closing valves, a conduit for the steel wire and manually operated means for actuating said steel wire to open 15 and close said air valves, said last mentioned means comprising a shaft extending through the main valve stem and formed at its inner end with an angular crank arm connected to said wire.
